ASEPTIC PUMP

Charles N. Nellis and Gino Mercuriali, Cedar Rapids, Iowa, assignors to Cherry-Burrell Corporation, Cedar Rapids, Iowa, a corporation of Delaware

Filed May 25, 1964, Ser. No. 369,898

2 Claims. (Cl. 103—87)

This invention relates to a pump and more particularly to a centrifugal-type pump that is suitable for use in aseptic processing systems where a sterile product is being handled.

With a constantly increasing demand for products which are purer and which have better keeping qualities, more and more processors of comestible products are utilizing systems in which the product is sterilized to destroy harmful bacteria and organisms that cause spoilage and shorten the shelf-life of the product. In order to preserve the sterility of a product, it must be handled after sterilization in equipment the design of which meets the highest sanitary standards. Thus, a demand has been created for pumps, fittings, valves, control elements, etc. which are suitable for use in such systems without the fear of contaminating the sterilized product.

All processing systems require some means for moving the product through the system of equipment. Therefore, where used, a pump is perhaps the most important component of such a system but it is also probably one of the most difficult components to design aseptically because of its moving parts. There are, of course, various types of pumps used in processing systems today, but this invention is directed primarily to a centrifugal pump of the rotary-impeller type, this type being commonly used in such systems.

It is therefore a principal object of this invention to provide a pump suitable for use in aseptic processing systems.

It is another object of the invention to provide an improved design of a rotary impeller pump which will permit the handling of a product thereby without the fear of contaminating the product even though leaks should develop in the seals used in the pump.

It is a further object of the invention to provide a rotary impeller-type pump in which all the seals are maintained in a sterile atmosphere by means of the introduction of a sterile gas in and around said seals.

It is a still further object of the invention to provide an aseptic pump of the rotary impeller-type which is suitable for use in aseptic processing systems and the design of which utilizes components of existing pumps to a maximum degree thereby standardizing a large number of parts and simplifying the manufacture of the pump.

It is a still further object of the invention to provide an aseptic pump the design of which is relatively simple, easy to manufacture and therefore relatively inexpensive even as compared to presently designed pumps not suitable for use in aseptic systems.

These and other objects of the invention will be readily apparent from a consideration of the following description taken in connection with the accompanying drawings in which:

FIG. 1 is a perspective view of the exterior of a pump of the type to which the invention relates;

FIG. 2 is a side elevational view with the driven portion of the pump in section in order to show the details thereof; and

FIG. 3 is a transverse sectional view taken on the line 3—3 of FIG. 2.

Referring to the drawings, the exemplary embodiment of the invention consists of a motor suitably enclosed by a housing 10 which is mounted on supporting feet 12.

2

The motor drives an impeller 14 inside of a volute-shaped pump housing 16 which has a product inlet 18 formed in the center thereof and a product discharge duct 20 that discharges the product tangentially from the housing 16.

5 On the pump side of the motor housing 10, there is a bell-shaped adaptor 22 which separates the motor housing 10 from pump housing 16. The pump housing 16 is connected to the bell-shaped adaptor 22 by means of a suitable clamping assembly 24 such as that shown in FIGS. 1 and 3. This permits the pump portion to be easily disconnected from the motor portion for maintenance or repair. The back cover 26 of the pump has a radial flange 27 around its outer edge 28 that is interposed between the adaptor 22 and the exterior pump housing 16, and thus, the back cover 26 is also held in place by the clamping assembly 24. Two axially spaced O rings 29 provide seals between the outer edge 28 of cover 26 and the pump housing 16.

Extending from the motor and through the center of 20 the adaptor 22 is a drive shaft 30 which extends into a coupling 34 on the end of impeller shaft 32. Key 36, fitted in suitable keyways in the coupling 34 and the drive shaft 30, and a set screw 38 or other suitable means may be used to secure the shaft 30 to the coupling 34.

The coupling 34 is welded or otherwise suitably affixed to the impeller shaft 32. The opposite end of impeller shaft 32 extends into the product zone through a hub 40 in the center of cover 26 that has a relatively large central opening 42 through it. At the outermost end of shaft 32 there is affixed the impeller 14 which is held in place by a nut 46 threaded on the end of shaft 32. Other suitable locking means may also be used. Since lubricants generally are not used in a pump designed for aseptic or sanitary use, there is provided a ring-shaped carbon seal 50 between the impeller 14 and an annular seat 52 against which the carbon seal 50 rotates. An O ring 54 is seated in a groove in the impeller shaft 32 inside of the annular carbon seal 50. Another O ring 56 is positioned in a groove formed in the outer periphery of the seal seat 52 and provides a seal between seat 52 and the opening 42 in the hub 40 of back cover 26.

A second carbon seal 58 is provided at the motor end of hub 40, the seal 58 being positioned between the coupling 34 and a seat 60 similar to seat 52 that is fitted inside the opening 42 in hub 40. Suitable O rings 62 and 64 provide seals between the carbon seal 58 and impeller shaft 32 and the seat 60 and hub 40, respectively.

The seats 52 and 60 for the carbon seals 50 and 58 are axially spaced-apart as shown in FIG. 2 and an open annular chamber 66 is thereby formed in opening 42 between the shaft 32 and the hub 40. A coil spring 68 or other resilient means is provided around shaft 32 in chamber 66 to bias the seats 52 and 60 apart against their respective seals.

55 The back cover 26 is somewhat dish-shaped and has two aligned radial ribs 69 connecting hub 40 and the outer edge 28. Each rib 69 has a boss 70 in the annular space between the hub 40 and the outer edge 28. A passageway 72 extends partially through each of the bosses 70 along a line parallel to the axis of the impeller shaft 32. The passageways 72 are each provided with a suitable fitting 74 for connection to a steam line 76. Radial passageways 78 in ribs 69 extend transversely of passageways 72 and interconnect them with the chamber 66 in hub 40. The passageways 78 also extend radially through the outer edge 28 of back cover 26 to an annular space 80 formed between edge 28 and pump housing 16. Thus, steam or some other sterile gas can be introduced into one of the steam lines 74 and will flow through the passageways 72 and 78 both to the chamber 66 and to the annular space 80. The steam will be discharged through

the other line 74. Thus, the seals provided by O rings 29 between the back cover 26 and the pump housing 16, the seals provided between the seats 52 and 60 by O rings 56 and 64, and the seals provided around the impeller shaft 32 by O rings 54 and 62 will all be encompassed by the sterile gas. Therefore, if a leak should develop in any of these seals, the positive pressure of the sterile gas will usually prevent contaminating matter from being passed into the product zone, and even if foreign matter did leak through the seals, it would be sterilized.

All the points of possible leakage from or into the product zone of the pump are sealed off with double mechanical seals as well as a steam seal. With the double seal arrangement, any leakage from the exterior into the product zone, or vice versa, is made very unlikely, and with the addition of a sterile gas introduced into the space between each set of seals, contamination of the product is practically impossible. This arrangement meets and exceeds the highest known sanitary standards.

Although the invention has been described only in connection with a certain embodiment and a certain type of pump, it will be obvious to those skilled in the art that various revisions and modifications can be made to the disclosed structure without departing from the spirit and scope of the invention. It is the intention, however, that any such revisions and modifications be included within scope of the following claims.

We claim:

1. An aseptic pump comprising a housing, a back plate separable from said housing and defining with said housing a product chamber, first and second seals extending continuously between the adjoining outer surfaces of said housing and back plate, said seals being spaced apart and defining an annular space between them, a product inlet and a product outlet in said housing, a rotatable impeller in said chamber to move the product through said inlet and discharge it through said outlet, power means to ro-

tate said impeller, a shaft extending through said back plate and operatively interconnecting said power means and impeller, inner and outer concentric seals between said shaft and said back plate, said seals being spaced apart axially with respect to said shaft to define an annular space around said shaft, means providing a first passageway in said back plate extending radially of said shaft and intercommunicating said annular space around said shaft and said annular space between said housing and back plate, means providing a second passageway in said back plate extending radially of said shaft and intercommunicating the said annular space around said shaft and the said annular space between said housing and said backplate, means providing an inlet to said first passageway between said annular spaces and adapted for connection to a source of sterilizing medium, and means providing an outlet from said second passageway between said annular spaces for exhausting said sterilizing medium from said space.

2. The aseptic pump of claim 1 in which said first and second passageways extend along radial lines 180° from each other.
